UNITED STATES PATENT OFFICE

123,314

DESIGN FOR AN OVER-DRESS ENSEMBLE OR SIMILAR ARTICLE

Henrietta A. Ruehl, New York, N. Y.

Application February 6, 1940, Serial No. 90,069

Term of patent 3½ years

To all whom it may concern:

Be it known that I, Henrietta A. Ruehl, a citizen of the United States, residing at 409 East 64th Street, New York city, in the county of New York and State of New York, have invented a new, original, and ornamental Design for an Over-Dress Ensemble or Similar Article, of which the following is a specification, reference being had to the accompanying drawing, forming a part thereof.

ensemble consisting of a slip on bolero jacket and a circular skirt showing my design.

Figure 2 is a rear elevation of Figure 1 showing the full length opening of the circular skirt at the back.

I claim:

The ornamental design for an over-dress ensemble or similar article, substantially as shown and described.
